[57] CLAIM

The ornamental design for a combination beach towel, hood, and poncho, as shown and described.

DESCRIPTION

FIG. 1 is a front elevational view of a combination beach towel, hood, and poncho showing my new design, the hood being shown separated;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a reduced perspective view thereof, the hood shown attached.

The broken lines shown throughout the views are understood to represent stitching.
